US0D1049407S

(12) **United States Design Patent** (10) Patent No.: **US D1,049,407 S**
(45) Date of Patent: ** Oct. 29, 2024

(54) **MASSAGER**

(71) Applicant: **Shenzhen S-Hande Technology Co., Ltd.**, Shenzhen (CN)

(72) Inventor: **Yumeng Du**, Shenzhen (CN)

(73) Assignee: **SHENZHEN S-HANDE TECHNOLOGY CO., LTD.**, Shenzhen (CN)

(**) Term: **15 Years**

(21) Appl. No.: **29/872,560**

(22) Filed: **Mar. 15, 2023**

(51) LOC (14) Cl. **24-01**

(52) U.S. Cl.

USPC **D24/215**

(58) **Field of Classification Search**

Primary Examiner — Michael A Maharajh

(57) **CLAIM**

The ornamental design for a massager as shown and described.

DESCRIPTION

FIG. 1 is a perspective view of a massager showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the massager that form no part of the claimed design.

1 Claim, 8 Drawing Sheets
